TRAIN DISPATCHING SYSTEM FOR
RAILROADS

Richard C. Leake, Rochester, N. Y., assignor to
General Railway Signal Company, Rochester,
N. Y.

Application November 22, 1928, Serial No. 321,186

16 Claims. (Cl. 246—3)

This invention relates to a train dispatching system of the type in which the dispatcher can control distant switch machines and in which trains are dispatched by wayside signal indications, and in which the control over the signals and switch machines and indications of train progress are transmitted over a comparatively few wires, by apparatus of the synchronous selector type.

10 In order that a dispatcher may properly dispatch the movement of trains, he should from time to time be informed as to the progress of trains along the track. This indication of train progress is known in signal parlance as OS-ing
15 train movements. It is understood by those skilled in railway practice that OS indications may come in simultaneously and in closely spaced overlapped relation, and for this reason a synchronous selector type system for transmitting such OS information lends itself to this function admirably, this because a synchronous selector system of the type hereinafter described permits the transmission of a very large number of distinctive indications over the same line wire in a very short period of time.

In accordance with the present invention, it is proposed to use a synchronous selector system in which a continuously operated distributor is located in the dispatcher's office and in which each way station along the railway track is equipped with a synchronous distributor, which, when required, is operated in synchronism with the selector in the dispatcher's office. In accordance with the present invention, if an OS signal is to be transmitted from a way station to the dispatcher's office, only the synchronous distributor at that way station is operated in synchronism with the selector, but when a particular signal or switch machine is to be controlled by the dispatcher each one of the way station distributors is operated. By this arrangement the way station distributors will be at rest a large part of the time. In accordance with the present invention it is further proposed to transmit a plurality of alternate positive and negative impulses over the stepping circuit including the synchronizing wire and the common return wire, the last impulse of which is either positive or negative, which last impulse determines whether the various way station distributors shall be operated during the next following series of impulses, or whether the way station distributors shall remain at rest, each subject to initiation from the way station at which it is located. Other features of the present in-

vention reside in the construction and arrangement of parts to establish synchronism between the various way station distributors with the dispatcher's selector, including means for stepping a way station distributor additional steps in the event it has not completed its entire cycle of operation.

Other objects, purposes and characteristic features of the present invention will in part be obvious from the drawings and in part be pointed out in the following specification.

In describing the invention in detail reference will be made to the accompanying drawings in which

Fig. 1A illustrates the equipment in the dispatcher's office;

Fig. 1B illustrates conventionally one embodiment of the track way apparatus located at a particular way station;

Fig. 2 shows on an enlarged scale a suitable 20 mechanical stick mechanism for maintaining a contact closed for a predetermined number of revolutions of a selector contact.

Fig. 3 shows the control and indication circuit of the system shown in Figs. 1A and 1B; and 25

Fig. 4 shows a modified control and indication circuit arrangement in which alternating current is superimposed upon direct current to obtain a larger number of indications through a limited number of control channels.

From the foregoing it is readily understood that the apparatus includes two rather distinct mechanisms and circuits, as follows:—(1) A stepping or synchronizing circuit and mechanism, which keeps the rotating selector contact and the rotating distributor contact at each way station in exact synchronism, and includes mechanism for normally holding all of the distributors at rest, but allows a way station distributor to start when an OS is to be transmitted from such station and allows all of the way station distributors to operate in synchronism with the dispatcher's selector when the dispatcher operates a lever to control a distinct function, and (2) control and indication circuits and mechanism, for transmitting over instantaneously completed circuits, completed by said stepping mechanism, control and indication impulses for controlling switch machines, wayside signals, OS signals, derails and the like.

Description of the system and apparatus.—Although the present system is applicable to both single track and double track railways, and is applicable to a large number of sidings and diverging routes, it has, for convenience, been

shown applied only to a passing siding PS connecting two single track sections and N and O of a single track railway system signalled with wayside absolute-permissive-block signalling.

5 In the particular arrangement shown the east end of passing siding PS is provided with entering signals 1 and 1^d and starting signals 2 and 2^d, and the west end of the passing siding includes entering signals 8 and 8^d and starting signals 7 and 7^d. At the east end of the passing siding PS is a track switch SE, operated by a switch machine SME, whereas the west end of this passing siding has associated therewith a track switch SW operated by a switch machine SMW. Each 10 of these track switches have the usual detector track circuit associated therewith, the east end detector track circuit includes the usual track battery and a track relay designated DE, and the detector track relay at the west end of the 15 passing siding PS is designated DW. These switch machines and signals are controlled from a dispatcher's office, and the detector track relay transmits OS signals to the dispatcher's office through suitable synchronously controlled mechanism, of which the distributor mechanism at the east end of passing siding PS has been designated SDE, and the distributor apparatus at the 20 west end of this passing siding has been shown schematically and designated SDW, and of which the synchronous selector mechanism located in the dispatcher's office, and shown in Fig. 1A of the drawings, has been designated SS.

In the dispatcher's office has been shown a miniature passing siding ps to represent the passing siding PS shown in Fig. 1B, indicating lamps IW and IE being shown and connected in the system to be illuminated when the detector track relays DW and DE are de-energized, respectively.

At the east end of passing siding PS are provided three control relays SMR, SR and DR for controlling the switch machine, the signal to proceed or stop and the direction of traffic respectively. Each of these relays is one of the permanent magnet stick polar type, which if momentarily energized by current of one polarity is operated to a particular position and remains in that position by magnetic flux from a permanent magnet until energized by current of the opposite polarity. The manner in which these relays control the switch machine and signals will be pointed out hereinafter.

The synchronous distributor mechanism for each of the various way stations is the same and for convenience the mechanism for the east end of passing siding PS only will be described. This mechanism comprises a distributor contact 10, which when rotated is adapted to co-operate with a stationary contact 11, a slip ring 12 and stationary contacts d⁰, d¹, d², d³, etc., to d²⁷. This distributor contact 10 may be rotated in any suitable manner, but in the particular arrangement shown is rotated by a suitable electrically operated spring-driven escapement mechanism including a pallet 15, escapement wheel 16, electro-magnet 17, co-operating with a permanent magnet 18 to reciprocate the pallet 15, the escapement wheel 16 being driven through suitable reduction gearing 19-20 and operated by a main spring 21, which main spring is wound up through the medium of ratchet wheel 22. The ratchet wheel 22 is held in its wound-up position by pawl 23, and is operated to wind up the main spring 21 through the medium of arm 24 and pawl 25 actuated by the spring 26. This spring 26 being elongated intermittently through the medium of pin-

ion 27 and sector 28 operated by the armature 29 of the winding magnet WM. It is thus seen that the main spring 21 can only be wound up to a tension corresponding to that of spring 26, the spring 26 being only tensionable to an extent 5 where arm 24 strikes the stop 30 and therefore has substantially a fixed tension. The distributor contact 10 is normally held at rest by the stop arm 31 held against the fixed stop 32 by the spring 33, this stop arm 31 being released 10 upon energization of the trip magnet TM. The distributor mechanism SDE also includes a quick-acting line relay LR, a medium-slow starting relay STR and a very slow blank repeating relay BR. 15

The synchronous selector mechanism in the dispatcher's office includes a selector contact 40, rotated by a worm gear 41, driven by a worm 42, connected on the shaft 65 of a chopper including commutator segments 43, 44, 45, 46, 47, 48, 49, 20 and 50, of which the segments 49 and 50 are connected to slip rings 51 and 52 respectively, these slip rings being connected to opposite terminals of a suitable battery 53. This chopper, or commutating mechanism, is driven by a motor M, and 25 also includes stationary brushes 53', 54, 55, 56, 57, 58, 59, 60, 61, and 62. Although the number of revolutions of the chopper per each revolution of the selecting contact 40 may be of any suitable ratio, for the purpose of facilitating description 30 of the particular embodiment of the invention shown a gear ratio, between the chopper shaft 65 and the selector shaft 66, of 18 to 1 has been selected, or in other words the worm gear 41 has 18 teeth. Suitable mechanism is required for 35 closing the synchronizing circuit for a particular number of impulses only, from which it appears that the point of making and breaking the synchronizing circuit to obtain such number of impulses must be very accurately determined, for 40 which the cam operated contacts 61, 68, 69, and 70 and the mechanical stick contact 71, operated respectively by the cams 72, 73, 74, and 75 and the magnet 76, are provided. The functioning of this apparatus is more readily described in 45 connection with the operation of the stepping or synchronizing mechanism. The selector contact 40 co-operates with stationary contacts s⁰, s¹, s², etc., to contact s²⁷.

In the dispatcher's office are also provided 50 levers LSME and LDE for controlling the switch machine relay SMR and the relays SR-DR respectively, similar levers LSMW and LDW being provided to control similar relays (not shown) at the west end of passing siding PS. There are also 55 provided indicating relays WR and ER for controlling the illumination of indicating lamps IW and IE, respectively, in response to deenergization of detector relays DW and DE, respectively. The functioning of this apparatus is more readily 60 described hereinafter under the heading, "Operation of Control and Indication Mechanism".

Operation of stepping and synchronizing mechanism.—As already stated the selector contact 40 65 is continuously driven by the motor M and rotates one complete revolution for each 18 revolutions of the motor. This selector mechanism SS in the dispatcher's office as shown in the drawings is assuming a position of blank, in which the stepping circuit including the synchronizing wire is open at contacts 69 or 70. Upon a few additional rotations of the motor M, however, the cams 74 and 75 assume a position to close contacts 69 and 70. The closure of contact 70 is immaterial 75

since the circuit in which it is included is open at the contact 71.

Closure of the contact 69 occurs at the beginning of a positive wave of current flow in the 5 stepping circuit, as determined by the commutator 49-50, and continued operation thereafter causes this plus impulse to be followed by successive minus and plus impulses. This stepping circuit may be traced as follows:—beginning at the 10 plus terminal of battery 53, wire 80, brush 62, ring 52, segment 50, brush 60, wires 81 and 82, cam contact 69, wire 83, cam contact 67, wire 84, synchronizing wire 85, wire 86, line relay LR, wires 87 and 88, common return wire C, wire 89, 15 brush 59, commutator segment 49, ring 51, brush 61, wire 90 back to the negative terminal of the battery 53. Continued operation of the selector mechanism SS causes 16 cycles, namely, a series of 16 positive and 16 negative impulses to be 20 transmitted to the line relay LR. The first or positive impulse will cause operation of the line relay LR to the dotted position and had the last impulse of the previous series of impulses been a positive impulse it would have allowed the 25 line relay LR to remain in its then dotted line position. After these 16 cycles of alternate impulses have been transmitted to the line relay LR, the contact 67 will be abruptly opened thus breaking the stepping circuit strictly at the end of a negative impulse, and during the next two revolutions of the motor M, bearing in mind that the worm wheel 41 has 18 teeth, although the contact 67 is abruptly opened and the contact 69 30 is abruptly closed, this is done so as to both make and break the circuit very quickly at the end of an impulse.

The line relay LR in response to the impulses just mentioned will apply current flowing in one 45 direction and then the other to the coil 17 on the pallet 15 of the escapement. Operation of this escapement pallet 15, however, at this time does not cause rotation of the distributor contact 10, because the distributor shaft 91 is held stationary by the stop arm 92 engaging the trip arms 31. It should be noted that the pole changer contacts 95 and 96 of the line relay LR apply 50 alternating positive, and negative, impulses to the period-of-blank relay or blank repeating relay 55 BR. This relay BR is a slow-acting relay and will not respond to the alternate positive and negative impulses, but will respond during the period of blank extending through two complete revolutions of the motor M for reasons heretofore explained, so that the relay BR is energized 60 during the 17th and 18th revolution of the motor M of a complete cycle of operation of the selector contact 40. Energization of the blank repeating relay BR closes the following circuit for rewinding the main spring 21 of the clock-driven escapement:—beginning at the battery 100, wires 101, and 102, contact 103 of the blank relay BR, wire 104, winding magnet WM, wires 105 and 106, back to the negative side of the 65 battery 100. With the winding magnet WM energized the armature is attracted to tension spring 26, and if the tension of spring 26 exceeds that of main spring 21 the escapement mechanism is rewound, thus keeping the tension of the main 70 spring constant. It is thus seen that normally 75

in response to continued operation of the selector mechanism in the dispatcher's office (see Fig. 1A) the line relay LR will be caused to be oscillated for a period of 16 revolutions of the motor M and will then leave the relay LR at rest in its left 5 hand position for the last two revolutions of this motor, and that this functioning of the line relay LR will cause the blank repeater relay BR to remain in its deenergized position during 16 revolutions, and will cause it to assume the energized 10 position during the next two revolutions. For reasons which will appear hereinafter the distributor contact 10 is not rotated under the conditions assumed.

Let us now assume that the detector track 15 relay DE at the east end of the passing siding PS is de-energized. Under this condition of relay DE the following circuit for energizing the starting relay STR is completed:—beginning at the battery 100, wires 101, and 107, front contact 108 20 of the blank relay BR, wires 109 and 110, distributor contact 10, wires 111 and 112, winding of the starting relay STR, wire 113, back contact 190 of the detector track relay DE, wires 115 and 106 to the negative terminal of the battery 100. 25 With this circuit completed the starting relay STR after a short period of relay assumes its energized position, this relay being slightly slow-acting, and effects closure of stick contact 114, thereby completing a stick circuit for this relay 30 which is the same as the pick-up circuit, just traced, except that the distributor contact 10 is shunted by stick contact 114. With the line relay LR in the left hand position and with the relays BR and STR energized the following circuit for 35 the trip magnet TM is completed:—beginning at the battery 100, wire 116, polar contact 95 in its left-hand position, wires 117, 118, 119, and 120, winding of the trip magnet TM, wire 121, resistance unit 122, front contact 123 of the starting relay STR, wires 124 and 125, contact 96 of the relay LR, wire 126 back to the negative terminal of the battery 100.

With this circuit completed the armature 31 is 45 attracted away from the stop arm 92 against the tension of the spring 33, thereby allowing the escapement wheel 16 to move only a very short distance where it is held by the escapement pallet, the distributor contact 10 remaining on the stationary contact d⁰. As the motor M in the 50 dispatcher's office continues to operate, the contact 69 is again closed at the beginning of a positive impulse, thereby transmitting alternate positive and negative impulses to the line relay LR. Since the distributor contact 10 is rotated step by step 55 in synchronism with the selector contact 40 in the dispatcher's office, these contacts 40 and 10 simultaneously engage contacts s¹, s², s³, etc. and contacts d¹, d², d³, etc., respectively. It is thus seen that various circuits connecting various devices in the tower and at the way station are completed momentarily in succession.

When the distributor contact 10 has made a complete revolution it is again stopped by the stop arm 92 engaging the armature 31, but since 65 the detector track relay DE is still de-energized, as assumed, the trip magnet TM is again energized during the period of blank, and the distributor contact 10 is again rotated during the next series of impulses. This will continue until 70 the detector track relay DE is again picked up, after which the distributor arm 10 will remain at rest, unless the dispatcher operates a lever in the dispatcher's office, as presently explained.

It has been pointed out that series of impulses 75

are transmitted from the dispatcher's office over the stepping circuit to the various line relays, and that normally each series comprises sixteen cycles of alternate positive and negative impulses making a total of thirty-two impulses. Since the first impulse has been assumed to be a positive impulse the last impulse will be a negative impulse. Also it will be noted that the worm gear 41 has eighteen teeth which would afford enough time to transmit eighteen cycles, but as already mentioned there is a period of blank corresponding to two cycles. Further, it is noted that only fourteen cycles or twenty-eight impulses are necessary to step the distributor contacts 10 at the various way stations entirely around and that sixteen cycles or thirty-two impulses are actually transmitted, from which it appears that two of these cycles or four impulses are ordinarily not used. The extra two cycles or four impulses 10 may for convenience be called synchronizing impulses, and serve to complete the revolutions of a way station distributor in the event it has lost one or a few steps for some reason or another. Under certain conditions, as pointed out herein- 15 after, there will be transmitted five additional impulses thus making the last impulse a positive impulse.

Let us now assume that the dispatcher operates one of the levers, such as lever LSME, for instance, and in so doing momentarily completes the following circuit:—beginning at the battery 130, wire 131, lever contact 132 closed momentarily, wire 133, coil 76 of the mechanical stick device SD, wire 134 back to the battery 130. 20 Momentary energization of the coil 76 attracts the armature 71, thereby causing the arm 135, held against the stop arm 136 by the spring 137, to drop off of the rest 138 and engage the worm 139, and thereby mechanically holds the armature 71 in its attracted position. The armature 71 will then remain closed through about five revolutions of the selector arm 40 at which time the pin 140 projecting from the shaft 66 lifts the arm 135 back on top of the rest 138, thereby 25 allowing the spring 137 to return this arm to its normal position against the stop 136, and allowing the armature 71 to be retracted by the spring 141. It is thus noted that a circuit including the armature 71 is closed at that point during 30 five revolutions of the selector arm 40.

With this armature 71 closed a multiple or branch circuit is completed bridging the contacts 67 and 69, which branch circuit includes the contacts 68, 70, and 71. It will be noted that the cams 74 and 75 are identical, so that the series of impulses are started at the same time irrespective of which of these two circuits are active. On the other hand, it should be noted that cam 72 has its contact closed only during the period of 35 16 complete cycles or 32 impulses, whereas the cam 73 has its contact closed through 16½ cycles or 33 impulses, so that with the contact 71 closed, a series of impulses is transmitted to the distant way stations of which series the last impulse is 40 a positive impulse, and therefore leaves the line relay LR in its right-hand dotted position during the period of blank.

With the line relay LR in its right-hand dotted position, and with the distributor contact 10 in 45 its locked position, the following circuit for the starting relay STR is completed upon picking up of the blank relay BR:—beginning at the battery 100, wires 101 and 107, contact 108, wires 109 and 110, distributor contact 10, wires 111 and 112, winding of the starting relay STR, wire 113,

front contact 142 of the relay DE, wires 143, 119, 118, and 117, contact 96 in its right-hand position, wire 126 back to the battery 100. With the starting relay STR energized and stuck up by its stick contact 114 the trip magnet TM is energized 5 through the circuit heretofore traced, thereby picking up the trip arm 31. With the trip arm 31 in its raised position the stop arm 92 is released, and since the escapement wheel can turn through an arc of substantially one-half tooth 10 before the left-hand anvil of pallet 15 is engaged, the distributor arm is moved to the position d¹. As the next series of impulses is transmitted from the dispatcher's office, the first impulse of which will be a positive impulse, the distributor 15 arm 10 will not be changed during this first impulse, because it has already taken a step corresponding to this positive impulse, the first negative impulse; however, will start the distributor arm 10 stepping, and cause this arm to be stepped 20 in synchronism with the selector arm 40 over the successive contacts. In the manner just described, the distributor arms 10 of all of the various way station distributor mechanisms will be rotated in synchronism with the selector arm 40 25 through five revolutions due to the transmission of five successive series of impulses, after which the stick device SD will open its contact 71, after which the last impulse of each series will again be a negative impulse, thus leaving the various 30 way station devices at rest thereafter, until either a detector track relay is dropped or the dispatcher again operates a lever.

It is thus seen that the selector mechanism in the dispatcher's office is operated continuously, 35 all the way station distributor mechanisms are operated through five revolutions each time the dispatcher operates a lever, and that upon the necessity of transmitting an OS indication from a way station to the dispatcher's office, the distributor at that way station is operated so long as the OS-ing condition persists. Instead of operating the entire system through five revolutions for each lever movement, it may be operated a less number of revolutions, all that is required is that it operate at least one complete revolution.

Operation of Control and Indication Mechanism.—Let us assume that there is an east bound train on the main track of passing siding PS, and that the dispatcher wishes it to proceed into the 40 single track section O. In order to do so he will move the lever LDE to the right-hand position thereby, for reasons heretofore given, causing the distributor arm 10 to be rotated in synchronism 45 with the selector arm 40, and momentarily transmitting a positive impulse to the direction relay DR, which impulse would operate this direction relay to the right-hand position did it not already assume this position. This circuit may be traced as follows:—beginning at the positive side of the 50 battery 150, in the dispatcher's office, through certain wires and devices as follows:—151, 57, 47, 48, 58, 152, 153, lever contact LDE, 154, S⁶, selector arm 40, selecting wire 155, 156, 157, winding of the direction relay DR, 158, contact d⁶, distributor 55 arm 10, ring 12, wires 159, 88, common return wire C, 89, 161, devices 56, 46, 45, 55, wire 162, back to the middle point of battery 150. Since the direction relay DR already assumed its right-hand position the position of this relay is not 60 changed. Also, with the lever LDE in the right-hand position a circuit is completed for operating the signal relay SR to the right-hand position as follows:—beginning at the positive side of battery 150, through certain wires and devices as 65 70 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130 131 132 133 134 135 136 137 138 139 140 141 142 143 144 145 146 147 148 149 150 151 152 153 154 155 156 157 158 159 160 161 162 163 164 165 166 167 168 169 170 171 172 173 174 175 176 177 178 179 180 181 182 183 184 185 186 187 188 189 190 191 192 193 194 195 196 197 198 199 200 201 202 203 204 205 206 207 208 209 210 211 212 213 214 215 216 217 218 219 follows:—**151, 57, 47, 48, 58, 152**, lever contact **163**, in its right-hand position, **164**, selector contact, **s⁷**, selector contact **40**, selecting wire **155, 156, 157, 165**, winding of the signal relay SR, **166**, distributor contact **d⁷**, distributor arm **10**, ring **12, 159, 88**, common return wire C, **89, 161, 56, 46, 45, 55, 162**, to the middle point of battery **150**. The momentary impulse transmitted to the signal relay SR, through the circuit just traced, operates the polar relay SR to its right-hand position where it is held by its permanent magnet until it has been energized by current of negative polarity. With the signal relay SR and the direction relay DR both assuming the right hand position, and with the switch machine in the main track position the signal **2** is operated to the clear position, providing traffic conditions in advance are clear, through a circuit readily traced in the drawings. Similarly if the lever LDE is operated to the left-hand position the direction relay DR is operated to the left-hand position but the signal relay SR is operated to the right-hand position, in which event, assuming the track switch to assume the main track position, the entering signal **1** may be cleared, if traffic conditions in advance are clear, through a circuit readily traced in the drawings.

Let us now assume that there is a west bound train travelling in the single track section O, and that the dispatcher wishes to allow this train to move on the side track of the passing siding PS. In order to do so, it will be necessary for him to first operate the track switch SE to the take-siding position, and to accomplish this the dispatcher will move the lever LSME to the left-hand position. Movement of lever LSME to the left-hand position will through the medium of contact **132** associated therewith operate the stick device SD to cause all of the way station distributors to operate through 5 successive revolutions of the selector arm **40**. Movement of the lever LSME to the left-hand position closes the following momentary circuit:—beginning at the negative terminal of the battery **150**, through certain wires and devices as follows:—**170, 53, 43, 44, 54, 171**, contact LSME in the left-hand position, wire **172**, selector contact **s⁸**, selector arm **40**, selecting wire **155, 156, 157, 165, 183**, winding of the switch machine relay SMR, wire **184** distributor contact **d⁸**, distributor arm **10**, ring **12, 159, 50**, common return wire C, **89, 161**, devices **56, 46, 45, 55**, wire **162** to the middle point of battery **150**. Completion of this circuit will transmit a momentary negative impulse to the switch machine relay SMR, thereby causing its contact to assume the left-hand dotted position in which it remains until it has been momentarily energized by current of the opposite polarity.

With the switch machine relay SMR in its left-hand position the switch machine SME is operated to the take-siding position only in the event all of the signals associated therewith are at stop, and providing there is no train approaching, as determined by suitable approach locking means more specifically disclosed in the application of S. N. Wight, Ser. No. 120,423 filed July 3, 1926. The dispatcher will then operate his lever LDE to the left-hand position thereby momentarily energizing the direction relay DR with current or reverse polarity and causing this relay DR to assume the left-hand dotted position. Also, with the lever LDE in the left-hand position a positive impulse is transmitted to the signal relay SR, thereby causing it to move to its right-hand dotted position. With these relays SR and DR in the positions just mentioned the take-siding signal

1^d is moved to the proceed position, bearing in mind that the switch machine SME now assumes the take-siding position, in which case the contacts **176** and **177** assume the dotted position.

As the west bound train in the single track section O accepts the take-siding signal **1^d**, and in so doing treads upon the detector track circuit and de-energizes the detector track relay DE the distributor SDE is operated in synchronism for reasons heretofore given and an impulse is transmitted to the indicating relay ER in the dispatcher's office over the following circuit:—starting at the battery **180**, wire **181**, back contact **182** of the detector track relay DE, wire **183**, distributor contact **d⁹**, distributor arm **10**, wires **159, 88**, common return wire C, **184, 185**, winding of the indicating relay ER, **186**, selector contact **s⁹**, selector arm **40**, selecting wire **155**, wire **156**, back to the opposite terminal of the battery **180**. The momentary completion of the circuit just traced energizes the indicating relay ER, thereby illuminating lamp IE and informing the dispatcher that the train in question has accepted the take-siding signal **1^d**. The indicating relay ER is preferably slow-acting so that it will remain energized during a complete revolution of the distributor contact **10**, and since the circuit just traced is completed momentarily during each revolution of the distributor contact **10**, and since this distributor will remain in operation so long as the detector relay DE is de-energized the indicating lamp IE will be illuminated so long as the detector track relay DE is de-energized.

As soon as the detector relay DE is again energized the indicating relay ER is de-energized and the lamp IE is extinguished. If the dispatcher, after having cleared the take-siding signal **1^d**, wishes to again put that signal to stop he will return his lever LDE to the middle position, in which case the magnet **76** is again energized, dropping the arm **135** into the worm **139** and causing the wayside selectors to operate through five cycles, and causing current of negative polarity to be momentarily applied to the signal relay SR during 5 successive revolutions of the distributor contact **10**, thus operating the signal relay SR to its left-hand position and breaking the energizing circuit for the signal **1^d**.

Operation of the system.—From the foregoing it readily appears that the operator may hold all of the signals at one end of a passing siding at stop or may clear any one of the signals, the selection of a particular signal being made through the direction relay DR and the position of the switch machine SME. For instance, if the switch machine assumes the main track position, the direction relay DR when it assumes the right-hand position will select east bound traffic and clear signal **2**, but if this direction relay DR is in the left-hand position west bound traffic is selected and signal **1** is cleared. On the other hand, if the switch machine SME is in the take-siding position, with the direction relay DR energized in the right-hand position east bound traffic may move, thus clearing the dwarf signal **2^d**, but if this direction relay DR is in its left-hand position, the take-siding signal **1^d** may be cleared, such clearing of the signal in each case depending on the position of the signal relay SR.

In practicing this invention a dispatcher may control the signal and switch machine at the ends of any passing sidings, and the dispatcher is informed by indicating lamps associated with the miniature track layout, a portion only of which has been shown, in the dispatcher's office of

the entrance and departure of trains to the ends of the various passing sidings. Attention is directed to the fact that the levers LSMW and LDW control the apparatus located at the west end of passing siding PS, the apparatus of which is identical to that already described, and this apparatus has been conventionally illustrated by the distributor contact 10^w and its associated contacts. Attention is directed to the fact that contacts 2, 3, 4, and 5 on the selector in the dispatcher's office and corresponding contacts on the distributor SDW are used for controlling the apparatus at the west end of passing siding PS.

It is also to be understood that the various way station distributors may be stepped around by any suitable stepping mechanism, such as ratchet means instead of the escapement type of mechanism shown. Further, the exact arrangements of circuits and devices used for starting a particular way station selector when an OS signal is to be transmitted from such way station and to start all of the way station selectors in the event the dispatcher operates a lever, need not be exactly as shown but may take any suitable form capable of carrying out the desired functions and coming within the scope of the appended claims.

Further, although each of the relays SMR, SR, and DR are polar relays of the permanent magnet stick type, and the relays WR and ER are neutral relays, neutral relays may be used at a way station and polar magnetic stick relays may be used in the dispatcher's office, or both types of relays may be located at both, or either, of these locations.

From the foregoing description it is apparent if a railway system is equipped with the apparatus described to each of its passing sidings, diverging routes and interlocked crossings that the dispatcher has absolute control over all of the trains, may cause a train to take the main track or a side track of a passing siding, may cause it to take a diverging route, may hold it at a railroad crossing, may hold a train on a main track or a side track of a passing siding, or putting it briefly may definitely control each train on the system. Also, it is apparent that the control of trains is much facilitated in that the dispatcher is informed from time to time as to the progress of trains, their speed and their location.

Modified structure of Fig. 4.—The system shown in Figs. 1A and 1B afford means for intermittently and in succession, connecting a plurality of circuit portions at a dispatcher's office with a plurality of circuit portions at various way stations, through the medium of a single line circuit, so as to transmit a large number of distinctive controls and indications over such line circuit. In accordance with the invention shown in Figs. 1A and 1B, these various controls and indications are carried out by the flow of direct current flowing in one direction or the other. In accordance with the invention shown in Fig. 4 of the drawings alternating current is superimposed on the momentarily completed direct current circuit, so that the number of indications over a single control channel is increased.

In order to simplify the description of the system as shown in Fig. 4, the stepping circuit and associated devices have been omitted, and for this reason the omitted features of Figs. 1A and 1B must be read into the drawing of Fig. 4 to make a complete system.

Further, in order to make it readily apparent what devices must be added in order to superimpose distinctive high frequency alternating currents on the various successively completed circuits shown in Figs. 1A and 1B, a simple circuit arrangement has been shown in Fig. 3 of the drawings illustrating the switch machine relay SMR circuit of Figs. 1A and 1B, in which all of the parts have been given like reference characters as in Figs. 1A and 1B. Fig. 4 is identical with Fig. 3 except for the apparatus necessary for superimposing alternating current upon direct current in accordance with the modified form of the invention.

Referring to Fig. 4 of the drawings it will be noted that the direct current control circuit including the lever LSME and the switch machine relay SMR in series has not been disturbed, or changed, except for the addition of the inductance 200 inserted at the lever end of the circuit and the inductance 201 inserted at the relay end of the circuit, neither of which materially affect the flow of direct current therein. In accordance with the particular embodiment of the invention shown in Fig. 4, a high frequency alternating current is employed for transmitting an OS indication from a way station to the dispatcher's office. For this reason, a double winding alternating current relay ER¹ is employed instead of a direct current neutral relay ER, and this indication relay ER¹ repeats its indication to the repeater indication relay RER¹, which in turn controls the indicating lamp IE. These relays ER¹ and RER¹ are so interconnected with the cam operated contact 203 as to cause the indicating lamp IE to be energized and remain illuminated for at least one revolution of the selector contact 40 after the energization of relay ER¹, as will be more clearly described hereinafter.

In order to complete the high frequency alternating current circuit for OS-ing purposes the switch machine relay SMR together with its inductance 201 are shunted by a back contact of the detector track relay DE, through a partial circuit including a condenser 204. It is noted that the control of the switch machine relay SMR by direct current is not interfered with, even though the detector track relay DE is de-energized, because direct current cannot flow through the condenser 204. Similarly, with the lever LSME in either its right or left-hand extreme position, direct current from the battery 150 cannot flow through the superimposed part of the circuit because current from battery 150 cannot flow through the superimposed part of the circuit including the high frequency generator HC and the upper winding of the indicating relay ER¹, because this circuit includes a condenser 205. It is thus noted that the switch machine SMR in the arrangement shown in Fig. 4 may be controlled in identically the same way as it is controlled in Figs. 1A and 1B and in Fig. 3.

Let us now consider the manner in which the indicating lamp IE may be energized in response to dropping of the detector track relay DE. Let us assume that a train is entering the right-hand end of passing siding PS (not specifically shown in Fig. 4) thereby closing the contact 206 of this relay, and dropping contacts 114 and 142 (not specifically shown in Fig. 4). Although with contact 206 open a very small amount of high frequency alternating current may flow through the upper side of the indicating relay ER¹, this current is unable to operate this relay ER¹ because it is too small in value by reason of the inductance 200.

201 included in the circuit. If now the contact 206 is closed, as has been assumed, the indicating relay ER¹ is picked up by reason of high frequency alternating current flow in the following circuit:—beginning at the high frequency generator HC, wire 207, upper winding of the indicating relay ER¹, wire 208, condenser 205, wires 209, and 172, distributor contact s⁸, selector arm 40, selecting wire 155, wires 156 and 210, back 10 contact 206 of the detector track relay DE, wire 211, condenser 204, wire 212, distributor contact d⁸, distributor arm 10, ring 12, wire 159 and 88, to the common return wire connected to the other side of generator AC.

15 With this circuit momentarily completed the indicating relay ER¹ is momentarily energized by current in its upper winding, and in response to closure of its front contact completes the following direct current circuit through its lower winding:—beginning at the battery 215, wire 216, contacts 203, wire 217, contact 218, wire 219, lower winding of the relay ER¹, wire 220, upper winding of the repeater relay RER¹, wires 221 and 222, back to the battery 215.

25 With this circuit completed the repeater relay is caused to assume its energized position in which the following stick circuit for this repeater relay RER¹ is completed:—beginning at the battery 215, wire 216, cam operated contact 203, wire 223, contact 224, wire 225, lower winding of the relay RER¹, wires 226 and 222, back to the battery 215. With the repeater relay RER¹ energized its front contact 227 closes an energizing circuit for the indicating lamp IE.

35 The cam operated contact 203 is operated by the cam 230, which cam is contained on the shaft 66 and is operated at the same rate of speed as is the selector arm 40. As is apparent from the drawing the cam 230 must make at least one complete revolution after energization of the relay ER¹ in order to extinguish the indicating lamp IE. Let us assume that the relay ER¹ and RER¹ are both energized, for reasons just explained, and that the cam 230 is operated in the right-hand direction as is the selector arm 40.

40 When the depressed part of the cam is engaged by the roller 232 the upper member of contact 203 is opened thereby breaking the circuit including the stick contact 224, but since the relay RER¹ is also energized by the current flowing through the lower winding of relay ER¹, this relay RER¹ remains in its energized condition. After a small fraction of a revolution of the cam 230, the roller 232 is engaged by the cam portion 231, thereby causing opening of the lower member of contact 203, and thereby breaking the stick circuit for lower winding of the relay ER¹ and effecting de-energization of this relay ER¹. The relay RER¹ remains energized, however, because the circuit for its lower winding is still closed. After substantially another complete revolution of the cam 230 the upper member of contact 203 is again opened thereby effecting dropping of the relay RER¹ and causing extinguish-

55 ment of the lamp IE unless the relay ER¹ has been picked up in the meantime. It is thus noted that the indicating lamp IE will be illuminated for more than one complete revolution of the selector contact 40, so that this indicating lamp will give a continuing indication in response to intermittent energization of the indicating relay ER¹, which intermittent energization is repeated so long as the detector track relay DE remains de-energized.

In accordance with the invention shown in Fig. 4 of the drawings, applicant has thus provided a system of the synchronous selector type in which alternating current is superimposed upon direct current in order to increase the number of controls and indications communicable over a single control channel. It is, of course, understood that the flow of direct current in the selecting circuit in response to operation of the lever LSME will not materially affect the flow of alternating current in the same selecting wire and common return wire, in response to closure of the detector track relay contact 206. It is desired to be understood that other circuit arrangements may be employed for transmitting both alternating and direct current over momentarily completed synchronous selector circuits within the scope of the present invention. Also, it is desired to be understood that other devices, such for instance, as the mechanical stick device SD may be used, instead of the cam operated contact 203 co-operating with the repeater relay RER², for maintaining the indicating lamp IE energized for at least one revolution after it has been illuminated.

25 Although two rather specific forms of the invention have been illustrated, in which specific apparatus has been shown and described for accomplishing specific functions, it is desired to be understood that many other forms of this invention, coming within the scope of the appended claims, may be used instead. For instance, other devices for closing the circuit through contacts 68 and 70 may be used instead of the mechanical stick device SD shown. Any number of contacts 30 may be used instead of the 28 contacts shown co-operating with the selector contact 40 and the distributor contact 10. As heretofore mentioned either thirty-two or thirty-three impulses are transmitted in a series depending upon whether 35 the device SD is in its circuit closing position or not, and from the structure it appears that only fourteen cycles, namely twenty-eight stepping impulses are necessary to step the distributor contact 10 entirely around the circumference. 40 This leaves four or five additional impulses transmitted after the distributor contact 10 is supposed to have completed its revolution, depending upon whether thirty-two or thirty-three impulses have been transmitted. These additional 45 impulses may for convenience be called clearing of synchronizing impulses, in that if the distributor contact 10 should have lost a positive and a negative step, and therefore is stepping two steps behind its theoretical position, this distributor 50 contact would be permitted to catch up, so to speak, and get back to its normal position ready for starting when the next series of impulses are transmitted. Similarly, any number of such 55 clearing impulses may be transmitted at the end 60 of the series, and the period of blank may be made as long as desired. Although the indicating relays ER and WR have been shown as slow-dropping neutral relays, these relays may be polar relays similar to relays SMR, SR, and DR, 65 and may be operated to one position when the detector track relay is in its retracted position and be operated to the opposite position when the detector track relay is again energized, suitable means being provided to stop the way station distributor a short time after the track relay is again energized. Also, although in the particular apparatus shown only the de-energization of the detector track relay is manifested in the tower by suitable indicating lamps, if desired, the posi- 70 75

tion of signals, the position of the switch machines and the condition of occupancy of the track circuits may be indicated in the dispatcher's office in the same way.

5 It should be understood that the chopper, comprising commutating segments 43—50, serves two important functions. In the first place it intermittently breaks the stepping circuit and also the message circuit by fast moving segments thus assuring that these circuits are made and broken at precisely the correct time, and thereby avoiding sparking at the selector contact 40. Secondly, it should be noted that the stepping circuit is only closed when the message circuit is open, and vice versa, and this assures that the flow of current in one of these circuits will not interfere with the proper functioning of the other circuit.

Further it is to be understood that even though a battery 159 has been illustrated, an alternating current source having a frequency of one cycle per each revolution of the shaft 65 may be used, it being understood that the voltage of the transformer would be in the proper direction during the communicating period. Also instead of applying the battery 53 to the stepping circuit by repeatedly reversing its terminals by devices as shown, an alternating current source may be used, either applied directly to the stepping circuit or applied intermittently as by placing a chopper such as the commutator 41, 48, 57, and 58 in series with the alternating current source.

Having thus shown, and described, several specific embodiments of a rather involved and comprehensive system, for carrying out certain functions, it is desired to be understood that the particular arrangement of devices and circuits illustrated need not be adhered to, but that many changes, modifications and additions may be made, in the individual devices as well as their co-ordination with each other, without departing from the scope or spirit of the invention as demanded by the scope of the appended claims.

What I claim is:—

1. A synchronous selector train dispatching system for dispatching train movements by wayside signal indications comprising, a dispatcher's office a plurality of way stations at distant points along a railway track, a selector in the dispatcher's office for connecting a line wire successively to a plurality of local circuits, a distributor contact at each way station for successively connecting said line wire to a plurality of circuits local to its way station, means in the dispatcher's office for transmitting successive positive and negative impulses to said way station distributors, and means for causing a particular way station distributor to operate in synchronism with the dispatcher's selector when an OS indication is to be transmitted from the particular way station distributor to the dispatcher's office and for causing all of the way station distributors to operate in synchronism with the dispatcher selector when the dispatcher operates a lever to control a distant traffic controlling device.

65 2. A synchronous selector train dispatching system for dispatching train movements by wayside signal indications comprising, a dispatcher's office, a way station, means at said dispatcher's office for transmitting to the way station either an even or an odd number of impulses of which the first impulse is of a particular polarity, a synchronous distributor located at said way station, and means causing the distributor to selectively operate in synchronism with said means.

75 3. A synchronous selector train dispatching sys-

tem for dispatching train movements by wayside signal indications comprising, a dispatcher's office, a way station, means for repeatedly transmitting to the way station a series of impulses of which the last impulse may be a positive or negative impulse depending on conditions at said dispatcher's office, said series of impulses being separated by a period of blank, and control means at the way station including a polar relay operated in response to said impulses and in a direction corresponding to the polarity of said impulses, and a slow-acting relay controlled by said polar relay constructed to assume its energized condition only during said period of blank.

4. A synchronous selector train dispatching system for dispatching train movements by wayside signal indications comprising, a dispatcher's office, a way station, apparatus in the dispatcher's office for transmitting series of successive positive and negative impulses of which the last impulse may be a positive or a negative impulse depending upon conditions in the dispatcher's office, the series being separated by a period of blank, a polar relay of the magnetic stick type responsive to said impulses and assuming a position depending upon the last impulse preceding said period of blank, a slow-acting relay controlled by said polar relay and assuming an energized position only during said period of blank, and a control circuit closed only if said slow-acting relay is energized and said polar relay assumes a predetermined position.

5. A synchronous selector train dispatching system for dispatching train movements by wayside signal indications comprising, a dispatcher's office, a way station, apparatus at said office for transmitting a series of positive and negative impulses to said way station separated by a period of blank, a polar line relay operated successively to opposite positions in accordance with the polarity of said impulses, a slow-acting relay controlled by said polar relay and assuming its energized condition only during said period of blank, step-by-step mechanism operated by said line relay, means for holding said step-by-step mechanism in the event said line relay assumes a particular position while said slow-acting relay assumes its energized condition.

6. A synchronous selector train dispatching system for dispatching train movements by wayside signal indications comprising, a dispatcher's office, a way station at a distant point along a railway track, a selector in the dispatcher's office for successively connecting a line wire to a plurality of local circuits, a distributor contact at a way station for successively connecting said line wire to a plurality of circuits local to said way station, means in the dispatcher's office for transmitting successive positive and negative impulses to said way station distributor, and control means associated with said dispatcher selector for at times only causing said way station distributor to operate in response to said impulses, and including a device for closing a circuit during a predetermined number of revolutions of a shaft and comprising in combination a shaft, a worm on said shaft, a device which if tripped from its normal condition will engage said worm at one end thereof, and means for restoring said device to its normal condition when said device has reached the other end of said worm.

7. In a synchronous selector type train dispatching system operable through cycles of operation, an indication circuit only momentarily completed during a cycle of operation of the sys-

tem, an indicating relay which is at times picked up during momentary completion of said indication circuit, a stick circuit for independently maintaining said indicating relay energized, a repeater relay having a pick-up winding included in said stick circuit, another stick circuit for said repeater relay, and means for alternately breaking the said two stick circuits.

8. In a synchronous selector type train dispatching system operable through cycles of operation, an indicating circuit only momentarily completed during a cycle of operation of the system, an indicating relay which is at times picked up during momentary completion of said indication circuit, a stick circuit for independently maintaining said indicating relay energized, a repeater relay having a pick-up winding included in said stick circuit, another stick circuit for said repeater relay, and means operated during a cycle of operation of the system for alternately breaking said two mentioned stick circuits following the momentary completion of said indicating circuit.

9. In a train dispatching system of the synchronous selector type, the combination with a distributor requiring a predetermined number of impulses from a pulsating source of current to operate the same and means for applying and disconnecting said pulsating source including two snap action cam operated contacts connected in series one of which closes the circuit gradually and opens it quickly and the other of which opens the circuit gradually and closes it quickly, said devices being so constructed that the gradually acting closing contact acts shortly before the quick acting closing contact and the gradually acting opening contact acts shortly after the quick acting opening contact.

10. In a synchronous selector train dispatching system, the combination with a local office and a plurality of way stations, of a plurality of message circuits each including the same line wire and common return wire, manually operable means for causing a cycle of operations during which cycle said message circuits are closed sequentially, automatic means for repeating said cycle of operation a predetermined number of times, and signals at each of said stations controlled over said message circuits.

11. In a centralized traffic controlling system for railroads, a control office, a plurality of field stations, traffic controlling devices at each field station, a selector type communication system operable step-by-step through cycles of operation and including two line wires connecting said control office and said field stations, means for transmitting either of two control conditions on each step of a cycle of operation from said control office to said devices at any particular station through the medium of said system and over said two line wires, and means for transmitting either of two indication conditions on each step of a cycle of operation from said particular station to said control office through the medium of said system and over said two line wires simultaneously with the transmission of controls over said two line wires.

12. In a communication system for railroads, a line wire connecting a control office and a field station, step-by-step means at the control office and at the field station operated in synchronism to successively complete a large number of channel circuits each of which includes said line wire, a direct current responsive device at the field

station and an alternating current responsive device at the control office both in one of said channel circuits, means for preventing said direct current responsive device from being affected by alternating current, means for preventing said alternating current responsive device from being affected by said direct current, means at the control office for supplying both direct and alternating current energy to said one channel circuit, means at the control office for controlling only the direct current in said one channel circuit, and means at the field station for controlling only the alternating current in said one channel circuit.

13. In a communication system for railroads, a line circuit connecting a control office and a field station, step-by-step means at the control office and at the field station operated in synchronism for a plurality of steps comprising a cycle of operation, means at the control office for energizing said line circuit on each step, means at the control office for distinctively controlling the energization of said line circuit on each step, controlled means at the field station responsive to said distinctive energization from the control office of said line circuit on each step, automatic means at the field station for selectively modifying the energization of said line circuit on each step without affecting the response of said controlled means, and means at the control office distinctively responsive to said energization of said line circuit on each step in accordance with whether or not such energization is modified by said automatic means at the field station.

14. In a communication system for railroads, a line circuit connecting a control office and a field station, step-by-step means at the control office and at the field station, means operating said step-by-step means through cycles of operation comprising a plurality of steps, means at the control office for energizing said line circuit on each step, manually governable means at the control office for distinctively controlling the energization of said line circuit on each of said steps, electro-responsive control means at the field station for each step distinctively responsive to the energization of said line circuit for that step only in accordance with said distinctive control of such energization at the control office, automatic means at the field station for distinctively controlling the energization of said line circuit on each of said steps without affecting the response of said electro-responsive control means, and electro-responsive indication means at the control office for each step distinctively responsive to the energization of said line circuit for that step only in accordance with said distinctive control of such energization at the field station.

15. In a communication system for railroads; two line wires connecting a control office and a field station; step-by-step means at the control office and at the field station operated in synchronism through cycles of operation, each cycle comprising a plurality of steps; a direct current source of energy in the control office; manually controllable means at the control office for selectively energizing said line wires with one polarity or the other on each step from said direct current source; an alternating current source of energy at the control office; an indication relay for each step; circuit means for connecting said alternating current source in series with said indication relay for each step to said line wires, whereby

- on each step said indication relay for that step is connected in series with said alternating current source to said line wires; a control relay at the field station for each step distinctively responsive to the polarity of direct current energization of said line wires for that step; automatically controlled contact means for each step at said field station; circuit means at said field station including said automatically controlled contact 5 for that step for allowing, when said contact is closed, the flow of alternating current in said line wires for that step without affecting the flow of direct current in said line wires for that step; means for causing each control relay to be unaffected by alternating current; and means in the control office for preventing interferences between the direct current and alternating current sources of energy.
16. In a communication system for railroads; 10 two line wires connecting a control office and a field station; step-by-step means at the control office and at the field station operated in synchronism through cycles of operation, each cycle comprising a plurality of steps; means at the control office for energizing said line wires on each
- 15

step with direct current; manually governable means at the control office for selectively determining the polarity of the energization of direct current on said line wires for each of said steps in accordance with the control to be transmitted for that step; direct current electro-responsive control means at the field station for each step distinctively responsive to the polarity of energization of said line wires for their respective steps for controlling their respective devices; an alternating current source of energy; means for connecting said alternating current source to said line wires on each step; means at the field station for selectively controlling on each step the flow of alternating current in said wires without affecting the flow of direct current in said line wires for that step, said means acting in accordance with the indication to be transmitted for that step; and alternating current electro-responsive indication means at the control office for 20 each step distinctively responsive to the flow or absence of alternating current in said line wires for that step for indicating the indication transmitted for that step.
